2 SHEETS—SHEET 2.

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,388,392.

Specification of Letters Patent. Patented Aug. 23, 1921.

Application filed January 4, 1919. Serial No. 269,562.

To all whom it may concern:

Be it known that I, JOHN WALDHEIM, a citizen of the United States, residing in Elizabeth, in the county of Union and State of New Jersey, have invented certain new and useful Improvements in Typewriting-Machines, of which the following is a specification.

This invention relates to typewriting machines, and more particularly to means for collating work-sheets of various sizes in various relative positions prior to typing on the collated sheets.

The present invention is shown applied in one form to an Underwood typewriting machine, and may comprise a collating board or table pivotally mounted upon a rod secured to the typewriter carriage, and which may be swung from a sheet-delivering position behind the platen to a forward or collating position where the work-sheets may be collated thereon.

The work-sheets may be collated relatively to each other by indices on the collating table and corresponding indices on the work-sheets, and may be held on said table by spring-controlled flaps which are hinged on said table so that they may be swung away therefrom during the sheet-collating operation.

The collating table, after the work-sheets have been adjusted thereon, is moved to a position back of the platen, so that the work-sheets thereon may be conveniently fed forward therefrom and introduced around said platen. To introduce the work-sheets around the platen, there are preferably mounted on the collating table feed-rolls, which may be manipulated by means of a finger-piece until the first writing line upon the work-sheets appears at the usual wing-scales at the front of the platen with reference to which the work-sheets may be accurately adjusted if necessary. Auxiliary to the collating table feed-rolls, the usual platen feed-rolls, which ordinarily coöperate with the typewriter platen, are provided and are automatically released when the collating table is moved to collating position. These platen feed-rolls are rendered effective by a finger-piece after the work-sheets have been adjusted around said platen, so that the work-sheets may then be line-spaced by the usual line-spacing mechanism after each line is typed.

55 A paper apron is provided, the upper end

of which is curved upwardly and forwardly to guide downwardly the leading ends of the work-sheets if they extend a considerable distance beyond the end of the collating table, with the result that the ends are directed downwardly toward the platen while the sheets are being collated on said table.

60 Other features and advantages will hereinafter appear.

In the accompanying drawings,

65 Figure 1 is a perspective view, showing the invention applied to the typewriter carriage, and the collating table swung to its collating position.

70 Fig. 2 is a sectional side elevation, showing parts in their normal writing position, and a work-sheet extending from the collating table around the platen.

75 Fig. 3 is a view similar to Fig. 2, but showing the collating table swung to its collating position, and the platen feed-rolls released.

Fig. 4 is a front elevation of Fig. 2, the upper part of the collating table being broken away.

80 Fig. 5 is a view of a portion of the collating table, looking endwise thereof, from the right in Fig. 3, but with one of the flaps swung away from the table for the purpose of placing work-sheets thereon.

85 A platen 9 is supported on a shaft 10 to rotate in a frame 11, which is provided with a paper apron 12 to assist in guiding one or more work-sheets 13 to and around said platen 9, so that they may be typed upon by the types upon type-bars 14. The platen 90 may be rotated after each line has been written by the usual line-spacing mechanism comprising a line-space handle 15, which, when operated, moves a slide 16 carried by the frame 11, rearwardly against the tension of a return spring 17, said slide having pivotally mounted thereon a line-space pawl 18 engaging with a ratchet wheel 20 secured to the platen shaft 10.

95 To assist in feeding the work-sheets 13 around the platen during the line-spacing operations, auxiliary front and back feed-rolls 21 and 22, respectively, are provided which are normally held against the platen by suitable springs 23, Fig. 4. These feed-rolls 21 and 22 may be released or cast off from said platen by a finger-piece or feed-roll release handle 24 secured to a stub shaft 25 mounted in said frame, said shaft having an arm 26 extending rearwardly, which is 100 105 110

moved upwardly when the finger-piece 24 is actuated to draw on a connecting link 27 connected at its lower end to an arm 28 extending from a rock-shaft 30, to rotate the latter in suitable brackets 31, Fig. 4, extending downwardly from and rigidly secured to a rod 32, extending between the side or end plates 33 and 34 of said frame 11, and upon which the front and back feed-rolls 21 and 22 are pivotally mounted through the intermediary of L-shaped members 35 and 36, respectively. These L-shaped members have downwardly-projecting fingers 37 and 38, which engage with flat faces 40 and 41 of the rock-shaft 30, Figs. 3 and 4. When the rock-shaft is rotated to the position shown in Fig. 3, the fingers are spread to swing the members 35 and 36 about the rod 32 and against the return springs 23 to cast off the front and back feed-rolls.

A collating table 42 is pivotally mounted eccentric to and clear of the platen 9 and preferably on a rod 43 above the platen and carried by ears 44 and 45 extending up from cover plates 46 and 47, secured to the end plates 33 and 34 of the platen frame by suitable screws. These cover plates may be similar to those used in the Underwood machine, except that they have the ears 44 and 45 formed thereon and are made of heavier material.

The collating table 42 comprises a back 48 and two sides 50 and 51, and normally occupies the position at the introductory side of the platen shown at Fig. 2, where the side 50 rests against a stop pin 52 projecting from the end 33 of the platen frame to hold the table nearly vertical. The collating table may be swung forwardly to a substantially horizontal position shown in Figs. 1 and 3, so that the sheets may be adjusted and assembled thereon. It may be held in this position by a stop pin 53 projecting from the side 51 of the collating table, said pin engaging on the upper side of the end plate 34. In order to assemble the work-sheets on the collating table 42, two flaps 54 are first swung up out of the way about suitable hinges 55 on the collating table. The work-sheets are then adjusted lengthwise of the collating table and relatively to each other according to indices or scales 56 on said table, and indices 57 which may be printed on the work-sheets. To assist in positioning the work-sheets crosswise of the collating table, there may be provided suitable side gaging means shown as comprising a plurality of pins 58 adjustable crosswise of the collating table in holes 60. These pins are shown only on the left-hand side of the collating table; it should be understood, however, that similar pins may also be provided at the other side. When the work-sheets have been adjusted relatively to each other, with suitable carbons therebetween, the flaps 54 are swung

down to hold the work-sheets against the table. The collating table 42 is swung from its collating position or sheet-receiving position to its sheet-delivering position at the introductory side of the platen, as shown in Fig. 2. The work-sheets are then advanced therefrom and introduced around the platen by a paper-feeding unit comprising feed-rolls 61, on said flaps and feed-rolls 62, on a shaft 63 supported on the side plates 50 and 51 of the collating table 42, said shaft 63 having a finger-wheel 64 preferably at the right-hand side thereof by which the feed-rolls may be rotated, and thus feed the work-sheets 13 from the collating table down to and around the platen. It will be seen that the operator may by manipulating these feed-rolls adjust the work-sheets to bring the desired writing line accurately to the printing point by alining the line with the usual wing-scales 65 arranged at the front of the platen as in the Underwood typewriting machine.

It should be understood that while the work-sheets are being introduced around the platen by the feeding unit on the collating table 42, the auxiliary or platen feed-rolls 21 and 22 are in their released position. To make certain that the path of the work-sheets is clear as they are introduced around the platen, the auxiliary feed-rolls 21 and 22 are automatically released when the collating table is swung forwardly to its collating position in Fig. 3. During the latter part of the forward swinging movement of said collating table, a pin 66 projecting from the side 50 of said table engages with an arm 67 extending upwardly from the shaft 25, upon which the feed-roll release handle 24 is mounted. This arm is swung forwardly to cause the arm 26 projecting rearwardly from said shaft to release the feed-rolls 20 and 21, as hereinbefore described.

After the work-sheets have been introduced around the platen and adjusted relatively to the scale 65 at the front of the platen, the operator manipulates the feed-roll release handle 24 to render the auxiliary feed rolls 21 and 22 effective, so that the work-sheets may be fed forwardly around the platen by the line-spacing mechanism including the line-space handle 15.

To have the flaps 54 light and as strong as possible, each flap comprises a body portion 70 which is hinged to the collating table at 55, and which is provided with bent-up ears 71 to support the feed roll 61. Detachably secured to said body portion is a guide wire 72 which is reduced at its ends 73 to enter turned-up receptacles 74, Fig. 1, on the body portion 70 of the flap 54, the wire guide 72 being additionally held on the body portion by spring fingers 75 on said flap. It will be seen that the flaps 54 are interdigitated to cover the back of the collating table, so that

when the collating table is in its sheet-delivering position, Fig. 2, the flaps are effective to prevent the upper ends of the work-sheets 13 and the side edge of a narrow sheet 76, 5 which extends only partway over the table, from falling rearwardly away from said collating table.

The interdigitation of the flaps may be had by bending the guide wires 72 to form 10 finger-like extensions 77, the extensions 77 of one guide wire extending into the spaces formed between the extensions of the other guide wire. The guide wires 72 are alike in construction and either one may be attached 15 to either flap.

To hold the flaps 54 in their effective or ineffective positions, each one is provided with a spring 80 which engages with a bent-off portion 81 on the body 70 of the flap, the 20 bent-off portion engaging in a depression 82 of said spring 80 when the flap is moved away from the collating table, as shown in Fig. 5. When the flap is moved down to its effective position, however, the bent-off portion 81 of the flap engages with the upper end or incline 83 of the spring 80 to press the feed-roll 61 against the coöperating feed-roll 62 on the collating table. It should be understood that the springs 80 may be located at any place lengthwise of the flap and 25 may be located nearer to the feed-rolls if found desirable.

To avoid any possible difficulty which might be otherwise experienced by work-sheets when the table is swung to the sheet-delivering position and especially when the work-sheets project a considerable distance beyond the edge of the collating table, there is provided at the upper end of the paper 35 apron 12 a curved extension or guard 84, which guides the ends of the work-sheets downwardly toward the platen, while they are being adjusted on the collating table, as seen in Fig. 1.

The guard 84 may be rendered ineffective, so that work-sheets may be inserted at the introductory side of the platen and in back of the collating table, thereby permitting the machine to be used independently of the 40 collating table. To do this, the curved guard 84 of the paper apron may be detachably supported on the table by fingers 85 and 86 engaging on the front and the back of the paper table.

From the foregoing description, it will be understood that two paper-feeding units are provided, that one of said paper-feeding units is preferably supported on the collating table and is effective to feed the work-sheets to a second paper-feeding unit, the latter including the platen, and that the 45 latter paper-feeding unit is effective to feed the work-sheets after they have been adjusted around the platen by the paper-feeding unit carried by the collating table. It

should also be understood that the device may be used to feed individual work-sheets into the machine, especially when it is desired to have the sheets squared with the platen and alined with a particular scale 70 marked crosswise of the platen, the side gage being provided on the paper table for this purpose.

Variations may be resorted to within the scope of the invention, and portions of the 75 improvements may be used without others.

Having thus described my invention, I claim:

1. In a typewriting machine, the combination with a platen frame, of a platen, plates comprising journals adapted to be made fast to said frame, and a collating table pivotally mounted in said journals back of said platen and adapted to be swung forwardly in said journals to a substantially horizontal position for the purpose of adjusting work-sheets thereon.

2. In a typewriting machine, the combination with a platen frame, of a platen, plates comprising journals adapted to be made fast to said frame, a collating table pivotally mounted in said journals back of said platen and adapted to be swung forwardly and away from said platen to a substantially horizontal position for the purpose of adjusting work-sheets thereon, feed-rolls 90 adapted to run upon the platen to feed the work-sheets, and means for holding the work-sheets on said table, and adapted to feed them to said feed-rolls to enable the 100 feed-rolls to grip them.

3. In a typewriting machine, the combination of a platen, a frame having journals to carry said platen, a collating table pivoted on said frame and at one side of said platen 105 journals, said collating table being adapted to be moved to a position for positioning work-sheets thereon with their faces up, said collating table being movable to a position to introduce the work-sheets around said platen at the receiving side thereof, driving means on the table to feed the work-sheets to the platen, and means to feed said work-sheets around said platen.

4. In a typewriting machine, the combination with a platen frame, of a platen, plates comprising journals adapted to be made fast to the frame, a collating table swingable on said journals to a position where work-sheets may be assembled thereon, a flap to hold the work-sheets on said collating table after they have been adjusted, a feed roll on said flap, a feed roll supported on said collating table, and means to actuate said feed rolls to feed the work-sheets around said platen.

5. In a typewriting machine, the combination of a platen, a collating table swingable to a position where work-sheets may be adjusted thereon, a flap to hold said work- 130

sheets on said collating table after they have been adjusted, a feed roll on said flap, a feed roll supported on said collating table, means to actuate said feed rolls to feed the 5 work-sheets around said platen, a feed roll engaging with said platen, means to automatically release said last-mentioned feed roll when the collating table is moved to its paper-adjusting position, and a finger-piece 10 to render said last-mentioned feed roll effective.

6. In a typewriting machine, the combination with a platen frame, of a platen, plates comprising journals adapted to be made fast 15 to the frame, a paper table pivotally supported in said journals, said paper table being swingable to a substantially horizontal position so that work-sheets may be adjusted on the back thereof, adjustable means on 20 said paper table whereby said work-sheets may be gaged, and means for holding said work-sheets on said paper table after they have been gaged, said means adapted to be driven to feed the sheets to the platen.

25 7. In a typewriting machine, the combination of a platen, a paper table pivotally supported at one side of said platen, said paper table being swingable relatively to said platen from a sheet-delivering position to a 30 position where work-sheets may be adjusted on the back thereof, means on said paper table whereby said work-sheets may be adjusted relatively to each other lengthwise of said paper table, means on said paper table 35 whereby said work-sheets may be positioned crosswise of said paper table, and a pair of flaps to hold said work-sheets on said paper table after they have been adjusted; said flaps being effective to hold said work-sheets 40 to prevent the free ends thereof from falling away from said table when the latter is moved back to its work-sheet-delivering position.

45 8. In a typewriting machine, the combination with a platen frame, of a platen journaled therein, a collating table pivoted on the platen frame eccentric to and above the platen to stand at the paper-receiving side of said platen and adapted to be swung 50 relatively to the platen forwardly and away from said platen to a substantially horizontal position for the purpose of adjusting work-sheets thereon, and driving means on said table for feeding the work-sheets around 55 said platen.

55 9. In a typewriting machine, the combination of a platen, a frame having journals to carry said platen, a collating table upon which work-sheets may be adjusted, 60 said collating table being pivoted on said frame eccentric to and above said platen to swing relatively thereto, means to hold said work-sheets on said collating table, and separate driving means for feeding said work- 65 sheets from said collating table around said

platen, said feeding means being carried by said collating table.

10. In a typewriting machine, the combination with a platen frame, of a platen, plates comprising journals adapted to be made fast 70 to the frame, a collating table pivotally mounted at one side of said platen on said journals and adapted to be swung forwardly and away from said platen to a substantially horizontal position for the 75 purpose of adjusting work-sheets thereon, means comprising a spring-pressed flap carried by said table for holding the work-sheets on said table, means for feeding the work-sheets around said platen; said last-named means comprising a feed roll on said 80 table and a feed roll on said flap; and a finger-piece to actuate said feed rolls.

11. In a typewriting machine, the combination of a platen, a platen frame in which 85 the platen is journaled, a collating table pivoted on the platen frame eccentric to and at one side of said platen and adapted to be swung relatively to the platen forwardly from a paper-delivering position to 90 a substantially horizontal position for the purpose of adjusting work-sheets thereon, means for holding the work-sheets on said table, feed-rolls for said platen, means to cast off said feed-rolls when said table is 95 swung to a paper-receiving position; said feed-rolls remaining in their cast-off positions when said table is swung back to a paper-delivering position, and driving means on said table to introduce the work-sheets around said platen. 100

12. In a typewriting machine, the combination with a platen and a platen frame having ends in which it is journaled, of a paper-table, a paper-apron, cover plates 105 adapted to be made fast upon said ends, a collating table journaled on said cover plates, and a curved extension adapted to be attached to said paper-table to guide down to the paper-apron and under the platen 110 work-sheets pushed rearwardly.

13. In a typewriting machine, the combination with a collating table, of two independent paper-feeding units, each unit comprising feed rolls, one of said units comprising a platen, the other feeding unit being effective to introduce a work-sheet around said platen from said table, a scale to indicate the extent through which the work-sheet may be fed around the platen by 115 said feeding unit, and means for driving said unit, the feeding unit comprising the platen being adapted to feed the work-sheet around said platen after it has been positioned relatively to said scale. 120

14. In a typewriting machine, the combination of a platen, auxiliary feed rolls, adapted to stand clear of the platen, a collating table, adjustable gages for work-sheets on said collating table, means for 125 130

holding said work-sheets on said collating table, driving means, including feed rolls, on said collating table to feed said work-sheets from said table and between the platen and 5 the auxiliary feed rolls, and means to render said auxiliary feed rolls effective, so that said work-sheets may be fed around said platen by rotation of the platen.

15. In a typewriting machine, the combination with a platen and a platen frame having ends in which it is journaled, of feed-rolls adapted to bear against the platen, a link for casting off said feed-rolls extending toward the top of one end, cover plates 10 adapted to be made fast upon said ends, a collating table journaled on said cover plates and adapted to be swung down forwardly for collating purposes, means whereby the downward movement of the table 15 actuates said link, a rear paper-table continuing into an apron, and a curved extension adapted to be attached to said paper-table to guide down to the paper-apron and under the platen, work-sheets pushed rear- 20 wardly.

16. In a typewriting machine, the combination of a platen, a platen frame in which the platen is journaled, auxiliary feed-rolls coöperative with the platen, a collating table 25 pivoted on the platen frame eccentric to the platen and swingable relatively to the platen from a sheet-delivering position in back of the platen to a sheet-receiving position, means to release the auxiliary feed-rolls 30 when said collating table is moved to said sheet-receiving position, means for holding work-sheets on said collating table, driving means, including feed-rolls, to feed the work-sheets from said collating table, when 35 the latter is in its sheet-delivering position, to a position where said work-sheets may be grasped between the auxiliary feed-rolls and said platen, means to render said auxiliary feed-rolls effective, and means to rotate said 40 platen to feed said work-sheets from said collating table.

17. In a typewriting machine, the combination with a platen and a platen frame having ends in which it is journaled, of a 45 paper-table, a paper-apron, cover plates adapted to be made fast upon said ends, a collating table journaled on said cover plates above the platen, so that an end projects down behind the platen to hold work- 50 sheets collated thereon, said collating table adapted to be swung down forwardly for collating purposes, and a curved extension adapted to be attached to the paper-table 55 to curve downwardly to the apron and under the platen work-sheets pushed rear- 60 wardly over the horizontal collating table.

18. In a typewriting machine, the combination of a platen, a platen frame in which the platen is journaled, a collating table in- 65 cluding a paper-gage, said collating table

being pivoted on the platen frame eccentric to the platen to swing relatively thereto from a sheet-delivering position at the introductory side of the platen to a substantially horizontal sheet-receiving position for 70 collating work-sheets thereon, paper-feed- 75 ing means to adjust a work-sheet around said platen according to its gaging at said gage in the sheet-delivering position on the collating table, a scale for indicating the writing line, and means for feeding said work-sheet by rotation of the platen after it has been adjusted.

19. In a typewriting machine, the combination of a platen, a platen frame in which 80 the platen is journaled, a collating table pivoted on the platen frame eccentric to the platen to swing relatively thereto from a sheet-delivering position at the introductory side of the platen to a substantially 85 horizontal sheet-receiving position upon which work-sheets may be adjusted, work- 90 sheet-feeding means on said collating table by which a work-sheet may be adjusted around said platen in the sheet-delivering position of the collating table, and means to feed said work-sheet around said platen by rotation of the platen after it has been ad- 95 justed.

20. In a typewriting machine, the combination of a platen, a paper-apron to guide work-sheets around said platen, a collating table adapted to be swung forwardly over the platen away from the apron so that work-sheets may be adjusted thereon rela- 100 tively to each other, and an extension of the paper-apron adapted to be attached thereto and curved at its upper end so that the work-sheets which project beyond the edge of the collating-table may be guided 105 toward the platen while said table is in its paper-adjusting position.

21. In a typewriting machine, the combination with a platen and a platen frame having ends in which it is journaled, of a 110 paper-table, a paper-apron, cover plates adapted to be made fast upon said ends, a collating table journaled on said cover plates, feed-rolls upon said collating table 115 adapted to grip work-sheets between them, a finger-piece for causing said feed-rolls to feed work-sheets to the platen, and holding devices adapted to hold the work-sheets to said table when swung on its journals.

22. In a typewriting machine, the combination with a platen frame, of a platen, journals adapted to be attached to said frame, a collating table swingable hori- 120 zontally over said platen in said journals, a relatively fixed paper apron, an extension 125 adapted to be attached to said paper apron, said extension being curved at its upper end so that work-sheets, when being adjusted on said collating table, may be guided down- 130 wardly toward the platen by the curved

portion of said paper apron, driving means for feeding said work-sheets to the platen after said table has been moved to its paper-delivering position, and means coöperating 5 with said platen to feed said work-sheets.

23. In a typewriting machine, the combination with a platen and a platen frame having ends in which it is journaled, of a paper-table, a paper-apron, cover plates 10 adapted to be made fast upon said ends, a collating table journaled on said cover plates, feed-rolls upon said collating table upon which work-sheets are adapted to lie, holding devices adapted to be swung clear 15 of the collating table to enable sheets to be collated, coöperating feed-rolls forming part of said devices to enable the work-sheets to be driven by the feed-rolls, and means detaining the holding devices in 20 either effective or ineffective position.
24. In a typewriting machine, the combination with a platen and a platen frame having ends in which it is journaled, of a paper-table, a paper-apron, cover plates 25 adapted to be made fast upon said ends, a collating table journaled on said cover

plates, feed-rolls upon said collating table upon which work-sheets are adapted to lie, holding devices adapted to be swung clear of the collating table to enable sheets to be 30 collated, coöperating feed-rolls forming part of said devices to enable the work-sheets to be driven by the feed-rolls, and means detachably mounted on the paper-table adapted to guide the collated work-sheets to the platen.

25. In a typewriting machine, the combination of a platen, a collating table upon which work-sheets may be assembled, and flaps upon the sides of the table comprising 40 interdigitated fingers adapted to hold the work-sheets on said table when the flaps are folded upon the table.

26. In a typewriting machine, the combination of a platen, a collating table having 45 a pivoted flap thereon, said flap comprising a body portion, and a guide wire detachably mounted on said body portion.

JOHN WALDHEIM.
